The ornamental design for a combined hole and embossment for a construction toy element, as shown and described.

DESCRIPTION

FIG. 1 is a perspective view of a combined hole and embossment for a construction toy element showing our new design;

FIG. 2 is a top plan view thereof; and,

FIG. 3 is a profile view thereof.

The broken line showing an outline of a toy construction block in FIGS. 1-3 is for illustrative purposes only and forms no part of the claimed design.
